UNITED STATES PATENT OFFICE.

ROBERT E. KIMBALL, OF CLEVELAND, OHIO.

COUNTER AND STACKER FOR TRANSFERS, TICKETS, AND THE LIKE.

1,317,979.

Specification of Letters Patent.

Patented Oct. 7, 1919.

Application filed October 22, 1915. Serial No. 57,285.

To all whom it may concern:

Be it known that I, ROBERT E. KIMBALL, a citizen of the United States, residing at Cleveland, in the county of Cuyahoga and State of Ohio, have invented a certain new and useful Improvement in Counters and Stackers for Transfers, Tickets, and the like, of which the following is a full, clear, and exact description.

10 This invention relates to a counter and stacker for tickets, street railway transfers, and the like, and has for its chief object the provision of an efficient counter and stacker by which tickets, and particularly thin 15 paper transfers, can be very accurately and rapidly counted and then stacked. In certain respects this invention is an improvement over the counting machines disclosed in my prior Patents No. 761,970, June 7, 20 1904, and No. 1,027,613, May 28, 1912.

One of the more specific objects is to provide means for preventing two or more of the devices to be counted from feeding through the machine at the same time. Further 25 objects are to avoid liability of folded or bent transfers stopping the continuous feeding and stacking. The above and other objects are accomplished by my invention which may be briefly summarized as consisting 30 in certain novel details of construction and combinations and arrangements of parts which will be described in the specification and set forth in the appended claims.

In the accompanying sheets of drawings, 35 wherein I have shown the preferred embodiment of my invention, Figure 1 is a top plan view of a counter and stacker; Fig. 2 is a side view looking toward the left of Fig. 1, parts being broken away; Fig. 3 is 40 a sectional view taken about midway between the side plates and showing the several feeding rolls; Fig. 4 is an enlarged sectional view substantially along the line 4-4 of Fig. 5; Fig. 5 is a top plan view 45 of a portion of the machine with some of the parts above the feed rolls removed; Fig. 6 is a transverse sectional view of a portion of the machine substantially along the line 6-6 of Fig. 5; Fig. 7 is a sectional 50 view substantially along the line 7-7 of Fig. 1, looking in the direction indicated by the arrows, this view showing particularly certain important parts of the mechanism for stopping the feeding action if two or 55 more of the devices being counted start to feed through the machine at the same time;

Fig. 8 is a top plan view of the same; Fig. 9 is a sectional view showing the same parts in side elevation, the section being taken substantially along the line 9-9 of Fig. 7 60 looking in the direction indicated by the arrows; Fig. 10 is a sectional view substantially along the line 10-10 of Fig. 1, certain parts being omitted and other parts being in elevation, this view showing some 65 transfers stacked; Fig. 11 is an inside elevation viewed from substantially the line 11-11 of Fig. 4, this view showing a transfer crimped or bent transversely and about to pass to the stacker.

70 The machine includes a frame composed chiefly of a pair of parallel side plates 10 from and between which the major part of the operating mechanism is supported. At one end of the machine there is an inclined 75 table or platform 11 upon which is adapted to be placed a pack of tickets, transfers or similar devices to be counted. As this machine is adapted particularly for counting transfers, the devices to be counted will 80 hereafter, for convenience, be termed transfers.

The transfers are placed with their edges 85 abutting the table 11 and are pressed yielding toward the feed rolls by a follower 12 which may be and preferably is connected by a link 13 to an arm 14 acted on by a suitable spring to cause the follower to gradually move the transfers up the table or platform 11. At the top of the table there is a 90 pair of feed rolls 15 which engage the foremost transfer and feed the same downwardly so that they pass one at a time between the rolls 16 and the edge of the table. The width of the gap between the table and 95 the rolls 16 can be varied by adjusting up and down a pair of strips 17. The rolls 15 are mounted on a shaft 18 and the rolls 16 are supported on a parallel shaft 19, both shafts being suitably supported in the frame 100 of the machine.

The transfers are fed downwardly and forwardly between the rolls 16 and a pivoted shoe 20, which, with the coöperation of other parts to be referred to presently, 105 is instrumental in stopping the feeding action of the rolls 15 and 16 if more than one transfer is fed at the same time between the rolls 16 and the shoe. The transfers are then fed down along a platform 21 between 110 upper and lower rolls 22 and 23 and thence between upper and lower rolls 24 and 25

and thence onto a series of rotating stacker rolls 26, the transfers being fed one at a time to the bottom of the stack which is formed under an L-shaped stacker member 27 which is slidingly mounted on an inclined plate 27^a, this stacker member 27 simply acting as a weight which bears on the stack of transfers being counted and stacked and gradually rises as the stack is built up from the bottom. The rolls 23, 25 and 26 are mounted on parallel driven shafts 28, 29 and 30 respectively, while the smaller upper rolls 22 and 24, which coöperate with the rolls 23 and 25, are friction rolls and are driven simply by contact with the rolls 23 and 25. These friction rolls are yieldingly supported on a bar 31 which extends between the side plates of the frame and which is preferably hinged at one end so that it may be swung upwardly, as shown by dotted lines in Fig. 3. At about the center of this arm 31 there is a transverse plate or shoe 32 upon which the rolls 22 and 24 are yieldingly supported and are spring-pressed downwardly by coil springs 33. The lower end of this shoe 32 projects downwardly between and below the top of the two rolls 25 and it serves to transversely bend thin paper transfers (see transfer "T" Fig. 11) at the center so as to substantially stiffen them and straighten the longitudinal edges in order that the transfers may feed beneath the lowermost transfer of the stack. It is often the case that street railway transfers are folded when handed to a conductor, and after they have been unfolded and are fed through a machine of this character they have a tendency to bend either up or down, but this shoe which bends the transfers transversely at the center overcomes the tendency for the transfers to catch at the stacking end and obstruct the feed of the oncoming transfers.

All the rolls except the friction rolls 22 and 24 have their peripheries covered with vulcanized rubber so that they will be able to frictionally engage and grip the transfers and cause them to be fed through the machine without any slipping. The friction roll 22 has a plain periphery while the friction roll 24 is provided with teeth, as will be observed particularly by reference to Fig. 4. This toothed roll performs the very important function of lifting the rear edge of a transfer if the transfer does not feed properly onto the stacker rolls and prevents it stopping the feed of the next or subsequent transfer.

It may be observed in passing that the stacker rolls 26 are not at all of the same diameter, but the rolls are of gradually decreasing diameter from the endmost to the center. This is also an important feature of the construction inasmuch as the transfers 65 then lie on a concave support which causes

the ends to be elevated (see transfer "T" Fig. 10). In other words, it prevents the ends of the transfers already stacked hanging or bending downwardly and permits the transfers to be fed without obstruction underneath the lowermost transfer of the stack. Instead of a series of separate stacker rolls, as shown, a single large concave roller may be employed as is obvious.

Power may be applied to drive the several shafts already referred to and other parts to be subsequently explained in any suitable manner, but in this instance the end of the shaft 35 which is beneath the shaft supporting the rolls 16 is provided with a pulley 36 adapted to accommodate a motor driven belt. This shaft is provided with a gear 37 which meshes with a gear 38 which is held frictionally by a clutch 39 onto the shaft 19 carrying the feed rolls 16. This gear 38, 85 through the instrumentality of the clutch 39, drives the shaft 19 when the transfers feed properly one at a time through the machine, but when two or more transfers pass at the same time between the rolls 16 and the pivoted shoe 20, a brake device holds the shaft 19 against rotation so that the gear 38 will slip on the shaft, as will be subsequently more fully explained.

Power is transmitted from the shaft 19 carrying the relatively large feed rolls 16 to the shaft 18 carrying the relatively small feed rolls 15 through a countershaft and a suitable train of gears, which will be designated as a whole by the reference character 100 40. Likewise, power is transmitted from the large gear 37 to the three shafts 28, 29 and 30 by gearing which may be designated as a whole by reference character 41. (See Figs. 1 and 2).

In conjunction with the feeding and stacking mechanism I employ a counter or register 42 which is supported at the side of the machine opposite to that having the driving pulley and transmitting gearing. 110 This register is preferably a set-back register containing novel construction and constitutes the subject-matter of a separate application, Serial No. 57,284, filed by me of even date herewith. On a shaft 43 extending between the register and the stacking machine proper there is a toothed driving wheel 44 which is intermittently but positively rotated by a pair of pins 45 which are carried by a shaft 46, each half revolution of which turns the toothed wheel through an arc equal to the distance between two adjacent teeth. It may be here stated that this particular driving means between the shaft 46 and the toothed wheel 44 is of 125 considerable importance for the reason that at the start and stop of each half revolution of the shaft 46 the two pins 45 have a substantially tangential sliding action on the teeth of the wheel 44, so that the toothed 130

wheel 44 and the shaft 43 which it drives are started and stopped slowly even though the intermittent driving impulses which are given to the shaft 43 are extremely rapid. 5 This driving feature, which is fully described in my companion application above referred to, prevents banging or hammering of the co-operating gears of the register and permits the use of a simple form of carrying mechanism in the register.

10 An escapement mechanism controlled and operated by the transfers as they are fed through the machine causes intermittent driving engagement between the shaft 46 and a continuously driven countershaft 47 (see Fig. 5) which is driven by gears from the shaft 35 to which the driving pulley 36 is attached, as previously described. On the inner end of the shaft 47 there is a toothed gear 48 and on the inner end of the intermittently operated shaft 46 there is a gear 49 which may be termed a flat gear as it is provided at two diametrically opposite points with flat or untoothed portions 49^a (see particularly Figs. 4 and 6). When either flat surface 49^a is opposite the teeth of the gear 48 the flat gear 49 is stationary, but if the latter is turned a predetermined amount, so as to cause the teeth thereof to be brought into driving engagement with the teeth of the driving gear 48, the said flat gear 49 will be rotated through a half revolution. This flat gear is turned sufficiently to bring its teeth into driving engagement with the teeth of gears 48 by each transfer as it passes through the machine. This is accomplished by a pair of fingers 50 which are diametrically opposite each other or 180 degrees apart, and which are secured to the inner end of the shaft 46 adjacent the flat gear 49, so that after each half revolution of flat gear 49 one of the fingers projects up into the path of movement of the transfer as it is fed between the rolls 22 and 23. Each transfer in passing between the rolls engages and shifts one of the fingers 50, causing driving engagement between the gears 48 and 49 and this causes the gear 49 to be turned through a half revolution, bringing the opposite finger in position to be engaged by the next transfer, and this action is repeated for every transfer fed through the machine.

55 This escapement mechanism is such that transfers can be fed extremely rapidly through the machine, the register being accurate at a rate as high as from 30 to 50 per second. For the purpose of preventing the gear 49 and the shaft 46 being turned 60 through more than one-half revolution per transfer fed through the machine, there is provided a rocking prong or yoke having a pair of upstanding fingers 60 and 60^a, said yoke being mounted upon a pin 61 and substantially straddling the shaft 46 upon which the gear 49 is mounted, as shown particularly in Figs. 4 and 6. The upper end of one of these two fingers 60^a of the yoke is adapted to be engaged at each half revolution of the shaft 46 by one of a pair of stop lugs or projections 62 which project at diametrically opposite points from a short sleeve which is secured onto the shaft 46 alongside the flat gear 49. This yoke tends at all times to swing to a position such that the upper end of the forward finger 60^a will be just beyond the path of movement of one of these lugs or projections, being given this tendency by the action of a pair of friction disks 63 such as leather pressed by a spring 63^a against a disk 64 loosely mounted on shaft 35 (see particularly Figs. 4, 5 and 6). This disk 64 is connected by a link 65 to an arm 66 projecting from the lower part of the yoke 60. However, just before the completion of the half revolution of the shaft 46 and flat gear 49, one of the lugs 62 engages the rear finger 60 of the yoke, rocking it so that the forward finger 60^a is moved into the path of movement of the opposite lug 62 so as to prevent the flat roll and fingers 50 overrunning, whereupon, by the friction of the disk 64, the yoke is rocked again to its normal position, permitting the further half rotation of the flat gear 49, when the escapement mechanism is operated by the next transfer, and this is repeated as long as the transfers are fed through the machine.

70 75 80 85 90 95 100 105 110 115 120 125 130

It may be noted at this point that the inner end of the shaft 47, supporting the gear 48, is mounted on an arm 67 which is pivotally mounted on a pin 68 and is pressed yieldingly toward the flat gear 49 by a coil spring 69. This construction minimizes shock as the teeth of the gears 48 and 49 come into engagement. The forward movement of the arm 67 and gear 48 may be limited in any suitable manner such as by means of a pin 67^a.

I shall now describe the mechanism for stopping the feed of the transfers through the machine when two or more transfers pass between the feed roll 16 and the shoe 20. This shoe is carried by a pin or finger 75 which is pivoted to an arm 76 secured to a shaft or rod 77 which is normally stationary and located below the rolls 16, as shown particularly in Fig. 4. This rod, the outer end of which is located beyond one of the side plates of the machine, has secured to its outer end a comparatively long arm 78 (see full line construction in Fig. 9 and dotted line construction in Fig. 6). The outer end of the arm 78 engages a relatively short arm 79 fixed to the inner end of sleeve 80 mounted to turn on a pin 81 extending out from one of the side plates 10 of the frame. This sleeve is surrounded by a coil spring 82 which tends to hold the short arm 130

1 or projection 79 in engagement with the longer arm 78 and to set the shoe 20 as will be subsequently explained. At the outer end of the sleeve 80 there is an upstanding arm 5 or finger 83 (see particularly Fig. 9) at the upper end of which there is a notch and shoulder and which is held by the spring 82 with the notched part engaging the outer end of a finger 84 which projects from a 10 disk 85 mounted loosely on shaft 19 between the hub of gear 38 (which, as previously stated, is held frictionally to the shaft 13 by clutch 39) and the hub of a disk 86 which is secured to shaft 19. Opposite surfaces of 15 this disk 86 are engaged by a pair of short plates 87 which extend up into a notch of a gripping device or clutch 88 which extends across and beyond both sides of the disk 86 as shown in Figs. 7 and 8. One end of this 20 gripping device is supported on a second arm 89 projecting outwardly from the disk 85 and the longer or inwardly projecting arm is engaged by the end of a rather weak coil spring 90.

25 While the finger 84 engages under the shoulder formed at the upper end of the upstanding finger 83, this gripping device is held at one end by the finger 83 and as it is engaged at the opposite end by the weak 30 spring 90 it causes the two plates 87 to engage with slight friction the disk 86, the normal degree of friction engagement depending solely on the pressure of the spring 90 which can be given any value desired.

35 When, however, the finger 83 is rocked so as to release the finger 84 immediately the gripping device 88 is carried forwardly with the disk until the end of the member 88 engages the end of a relatively stiff spring 91, 40 which absorbs the momentum of the moving parts and then positively locks the disk 86 against movement and so stops the rotation of shaft 19 and of the feed rolls 15 and 16. This occurs whenever two or more transfers 45 are fed between the rolls 16 and the shoe 28.

Initially the shoe 20 is set at exactly the desired distance from the rolls 16, this distance being equal to the thickness of the transfer to be fed through the machine. 50 This is done by loosening the finger 83 from sleeve 80, placing a transfer between the shoe 20 and the rolls 16, and permitting the spring 82 to press the shoe up against the transfer. The said spring accurately sets 55 the shoe and eliminates all loose play between the connecting or engaging parts.

After the spring has positioned the shoe the finger 83 is brought up against the finger 84 and is tightened on the sleeve 80. When this 60 is done, as long as the transfers are fed one at a time between the rolls 16 and the shoe 20 (and it may be here stated that they feed one at a time unless two transfers are stuck together) the machine operates without interruption and the finger 83 remains against

the end of finger 84. Just as soon, however, as two or more transfers pass between the shoe 20 and the rolls 16 the shoe is moved away from the roll 16 a distance equal at least to the thickness of a transfer. Due to 70 the lever arm 76 (Fig. 4) and the difference between the lengths of the lever 79 and finger 83, this slight movement of the shoe is very much multiplied at the outer end of the finger 83 and is sufficient to rock the finger 83 until it is clear of or free from the end of the finger 84. As soon as this occurs the disk 86 is immediately gripped by the plates 87 through the action of the gripping device 88 and the rotation of the shaft 19 is 75 stopped, stopping the rotation of the rolls 15 and 16 as above explained. This stopping mechanism, delicate as it is, (being controlled by the thickness of a thin paper transfer) is extremely reliable in operation 80 as it does not fail to stop the feeding action if two transfers are fed at the same time or if a folded transfer is fed through the machine causing a double thickness of material 85 to pass between the shoe 20 and rolls 16. 90

By way of explanation of the operation of the machine as a whole, it may be stated that prior to counting a pack of transfers the operator will set the set-back register 42 to zero and will place the transfers on the table 11, 95 and when the machine is set in operation if it had not been previously started the transfers will begin to feed through the machine and will be stacked upon the stacker rolls gradually lifting the stacker device 27, each 10 transfer being pulled inwardly at the bottom of the stack. As each transfer passes between the rolls 22 and 23 it engages one of the upstanding fingers 50 and shifts the same a sufficient amount to cause the teeth of 10 the flat gear 49 to engage the teeth of the continuously revolving full toothed gear 48 until the shaft 43 is turned through a half revolution, when it will stop. This causes the toothed wheel 44 to turn through one 1 counting space, the starting and stopping movement of this wheel 44 being slow, as previously explained.

The transfers are in this manner fed continuously and rapidly through the machine, 1 each transfer being counted on the register. When the last transfer is set through the machine and is counted the operator can then set back the register to zero after noting the count on the counting wheels and the 1 operation can then be repeated for another set of transfers.

As previously explained, even if the transfers were previously folded and are creased because of such folding, as they pass between the rolls 24 and 25 they are transversely bent at the center by the shoe 32 and are thus stiffened, causing the front edges to straighten so that they can move under the lowermost transfer of the pile being stacked.

And in the event the forward movement of one of the transfers is stopped or slowed down as it passes the contacting portions of the rolls 24 and 25, the teeth of the former will engage the rear edge of the transfer and lift it up in such a way that the next transfer can pass underneath it.

In the event that two transfers are stuck together and simultaneously passed between the rollers 23 and the shoe 20 the shoe 20 is moved downward an amount equal to the thickness of a transfer. This rocks the shaft 77 carrying the shoe and this movement is multiplied through the instrumentality of the several levers causing the latching finger 83 to be moved out of engagement with the finger 84 and permitting the clutching or gripping device 88 to stop the rotation of the shaft 19 through which the forward feed rolls 15 and 16 are operated. When this occurs the feeding of the transfers is, of course, stopped until the operator extracts the two transfers from between the shoe and rolls 16, whereupon the feeding, counting and stacking continues. The operator will extract the two or more transfers from between the shoe and rolls 16 by turning the rolls backward and this automatically resets the fingers 83 and 84. A pin 92 prevents the finger 84 turning backward too far.

While I have shown the preferred form of my invention, it is obvious that numerous changes may be made in the arrangement and details and form of the parts which are employed to carry out the principle of my invention, and I, therefore, do not desire to be confined to the particular form of the invention here shown, but aim in my claims to cover all modifications which do not involve a departure from the spirit and scope of my invention. It is to be understood also that the machine is not limited in the use to the counting of street railway transfers.

Having thus described my invention, what I claim is:—

1. In a machine of the character described, a frame having side walls, a support at one end of the frame adapted to receive a pack of transfers, tickets or similar devices, a stacker at the opposite end of the frame adapted to receive the devices, means comprising feed rolls for conveying the devices from said support to the stacker, shafts for operating said feed rolls journaled in the side walls of the frame, a member extending between the side walls of the frame and provided with rolls which coact with said first-named feed rolls to perform the feeding operation, and provided between two of said first named feed rolls adjacent the stacker with means for transversely bending said devices just before they pass to the stacker.

2. In a machine of the character described, a frame, a support adjacent one end

of the frame adapted to receive a pack of transfers, tickets, or similar devices, a stacker adjacent the opposite end of the frame and comprising a rotating member on which the devices are gradually stacked when the machine is in operation by being fed one at a time to the bottom of the stack, feeding means between said support and the stacker and serving to deliver said devices in a plane adjacent to the upper surface of said rotating member of the stacker.

3. In a machine of the character described, a frame, a support adjacent one end of the frame adapted to receive a pack of transfers, tickets, or similar devices, a stacker adjacent the opposite end of the frame and comprising a rotating member on which the devices are gradually stacked when the machine is in operation by being fed one at a time to the bottom of the stack, feeding means between said support and the stacker and serving to deliver said devices in a plane adjacent to the upper surface of said rotating member of the stacker, and means adjacent to and in advance of the stacker for bending said devices so as to stiffen them and form their front edges so that they will pass without hindrance to the bottom of the stack on the stacker.

4. In a machine of the character described, a support for a plurality of transfers, tickets or similar devices, a stacker adapted to receive and hold the devices, feeding means for feeding the devices from the support to the bottom of the stack on the stacker, said stacker being concave or lower at the center than at the ends.

5. In a machine of the character described, a support for transfers or other devices, a stacker adapted to receive and hold the devices, and feeding means for feeding the devices from the support to the stacker, said stacker being an annular rotating means of decreasing diameter from the ends inward.

6. In a machine of the character described, a support adapted to receive a pack of transfers, tickets or other devices, a stacker adapted to receive the devices, feeding means for feeding the devices from said support to the stacker and comprising a plurality of rolls, including an upper and a lower roll between which the devices pass, said upper roll having teeth adapted to lift the rear edges of the devices.

7. In a machine of the character described, a support adapted to receive a pack of transfers, tickets or other devices, a stacker, feeding means, means for feeding the devices from the support to the stacker, including a plurality of driven rolls and a roll which is adapted to frictionally engage one of the driven rolls, said frictionally driven roll having teeth on its periphery.

8. In a machine of the character described, a support for a plurality of transfers, tickets or similar devices adapted to be counted, a receiving member for said devices, feeding means for feeding said devices from the support to the receiving means, and means for stopping the feed of said devices if two or more of the latter pass a given point at the same time, said stopping means comprising a device for locking the feeding means against movement.
9. In a machine of the character described, a support adapted to receive a plurality of transfers, tickets or similar devices, means for feeding said devices along a given path, said means including a plurality of rolls, a movable member arranged adjacent one of said rolls so as to permit said devices to pass one at a time between said member and the associated roll, and means operated by the movement of said member away from the roll when two or more of the devices pass between the roll and said member at the same time for stopping the feed of said devices, said feed stopping means comprising a member for positively stopping the feed rolls.
10. In a machine of the character described, a support for a plurality of transfers, tickets or similar devices to be counted, means for feeding said devices along a given path, a movable member arranged adjacent one part of the feeding means and adapted to be moved when two or more of the devices are fed past said members at the same time, and means operated by the movement of said member for stopping the feeding operation, said last mentioned means comprising a device for locking the feeding means against movement.
11. In a machine of the character described, a support for a plurality of transfers, tickets or the like, means for feeding said devices along a given path, and including a roll and a shaft for driving the same, means normally operating said shaft when the devices are fed one at a time, and means for stopping the operation of said shaft when two or more of the devices are fed past a given point at the same time, said stopping means comprising a movable device for locking said shaft against movement.
12. In a machine of the character described, a support for a plurality of devices to be counted, a feeding means for feeding the devices through a given path, means for operating said feeding means including a shaft, and means for holding said shaft against movement when two or more of the devices pass a given point along the feeding means at the same time.
13. In a machine of the character described, a support for a plurality of transfers, tickets or similar devices to be counted, feeding means for feeding said devices along a given path including a plurality of rolls, and a driving shaft for at least one of the rolls, a movable member arranged adjacent one of said rolls so that the devices as they are fed pass between said member and the associated roll, and means controlled by the movement of said member when two or more of the devices pass between said member and the associated roll at the same time for locking the shaft against movement.
14. In a machine of the character described, a support for a plurality of transfers, tickets or similar devices to be counted, feeding means for feeding said devices along a given path, said means including a plurality of rolls, a driving shaft for at least one of the rolls, a movable member arranged adjacent one of said rolls so that the devices as they are fed pass between said member and the associated roll, and means controlled by the movement of said member when two or more of the devices pass between said member and the associated roll at the same time for locking the shaft against movement, and means whereby the normal distance between said member and the associated roll may be set or adjusted.
15. In a machine of the character described, a support adapted to receive a plurality of transfers, tickets or similar devices to be counted, feeding mechanism for feeding the same along a given path and including a roll, a shaft on which the roll is mounted, and means for driving the same, and means for stopping the feeding operation if two or more of the devices pass a given point at the same time, said means including a movable member adjacent said roll, a locking device for positively stopping and holding said shaft against movement, and movement multiplying mechanism between said member and said device.

In testimony whereof, I hereunto affix my signature.

ROBERT E. KIMBALL.
